[57] CLAIM

The ornamental design for a bottle inversion cap, as shown and described.

DESCRIPTION

FIG. 1 is a top plan view of an improved design for a bottle inversion cap in a closed position,

FIG. 2 is a front side elevational view of the bottle inversion cap,

FIG. 3 is a perspective view of the bottle inversion cap, in a closed position; and,

FIG. 4 is a perspective view of the bottle inversion cap, in an open position.

The surface(s) or portion(s) of the article not shown in the drawing or described in the specification form(s) no part of the claimed design.
